UNITED STATES PATENT OFFICE.

EDUARD ENDERS, OF DUSSELDORF, GERMANY.

HAT-FASTENER.

SPECIFICATION forming part of Letters Patent No. 678,723, dated July 16, 1901.

Application filed April 29, 1901. Serial No. 57,972. (No model.)

To all whom it may concern:

Be it known that I, EDUARD ENDERS, a subject of the German Emperor, and a resident of Dusseldorf, Germany, have invented certain new and useful Improvements in Hat-Fasteners, of which the following is a specification.

My present invention relates to hat-fasteners, the object being to provide an improved device of this kind whereby the ordinary objectionable pins or other devices may be dispensed with, the improved fastener enabling the hat to be easily and readily attached and detached, as hereinafter described.

The invention consists in the construction, combination, and arrangement of parts, fully described and claimed hereinafter, reference being had to the accompanying drawing, showing the preferred form of construction of my improved hat-fastener.

Referring to the drawing, 1 represents a coiled spring shaped in accordance with the edge of the hat to which the device is to be applied and surrounding a flat twisted spring 2, serving to transmit the rotation, as hereinafter described. Arranged on said coiled spring are three or more sleeves 3, carrying suitable hooks 4, adapted to pass through the material of the hat for the purpose of attaching the device to the latter. The coiled spring 1 is provided with a plurality of preferably integral hooks 5, which when said spring is rotated are adapted to grasp the hair of the user and fasten the hat on the head of the latter. In order to enable the spring 1 to be readily rotated, one end of a flat spring 2 is provided with a small gear-wheel 6, meshing with a toothed pinion 7, fast on a shaft 8, provided with an operating button or knob 9, as shown. Said shaft 8 is attached to the hat by means of hooks 10.

The device being constructed as described, it is attached by means of the hooks 4 and 10 to the hat, along the inner edge thereof. When the user desires to fasten the hat, she has but to actuate the knob 9 in the direction of the arrow, whereby the several hooks 5 are moved into the hair to effectively fasten the hat.

In order to prevent the hooks 5 from mak-

ing a complete revolution, the pinion 7 is preferably toothed only over a portion of its periphery.

I wish it to be understood that many changes and modifications may be made in the construction shown and described without departing from the scope or sacrificing any of the advantages of my invention.

Having fully described my invention, what I claim, and desire to secure by Letters Patent, is—

1. In a hat-fastener, the combination with a coiled spring bent in accordance with the shape of the hat, of a flat twisted spring arranged within said coiled spring, integral fastening-hooks on the latter adapted to engage the hair of the user, means for rotatably attaching said coiled spring to the hat, and means for rotating said spring, substantially as set forth.

2. In a hat-fastener, the combination with a coiled spring bent in accordance with the shape of the hat, of a flat twisted spring arranged within said coiled spring, integral fastening-hooks on the latter adapted to engage the hair of the user, a plurality of sleeves loosely fitted over said coiled spring, suitably-shaped attaching-hooks on said sleeves and means for rotating said coiled spring, substantially as set forth.

3. In a hat-fastener, the combination with a coiled spring bent in accordance with the shape of the hat, of a flat twisted spring arranged within said coiled spring, integral fastening-hooks on the latter adapted to engage the hair of the user, a plurality of sleeves loosely fitted over said coiled spring, suitably-shaped attaching-hooks on said sleeves, a small gear-wheel on one end of the flat spring, a partially-toothed pinion on a rotary shaft, and meshing with said gear-wheel, and an operating-knob, or equivalent, on said shaft, substantially as set forth.

In testimony whereof I have hereunto set my hand in presence of two witnesses.

EDUARD ENDERS.
